Krauth & Benninghofen, Hamilton, Ohio

Application February 24, 1933, Serial No. 658,329

4 Claims. (Cl. 282—16)

This invention relates to improvements in autographic registers or manifolding machines, dealing with a continuous strip in one or a plural number, fed from a supply compartment upon a writing table or platen and withdrawn therefrom in determined sheet lengths which are severed or torn from the strip. The strips generally contain printed blank forms as sales strips with apertures usually in the spacing between the forms, 5 to serve as filing holes, for each form length after issuing from the machine and torn or severed from the strip and as indexes for the strips while within the machine limiting the withdrawal either manually or mechanically to definite and measured sheet lengths; for aligning or registering the 10 printed form matter of the several strips upon the writing table and avoiding the possibility of the manifold strips creeping on one another or to disturb their registry with the uppermost strip 15 and also as in the present invention, for making a positive connection with the strips for administering a mechanical pull out or feeding advance of the strips or project the ends thereof from the machine for manual grasp so that the pull out or 20 advance can be continued manually for a length determined by the aperture spacing longitudinally of the strip.

An object of the invention is to provide means for mechanically advancing a plurality of strips to project an end thereof from the machine for hand grasp to manually continue the withdrawal for a determined or measured length with one of the strips of the series coordinately with the withdrawal of the others fed into a record compartment within the casing of the machine.

Other features and advantages of the invention will be more fully set forth in the description of the drawings in which:

Figure 1 is a plan view of the improved autographic register or manifolding machine as charged with sales strips with part of the machine frame at one end of the machine, broken away to expose parts that would be hidden thereby; likewise the cover for the opposite end of the machine is shown as swung back to illustrate the record strip deposited within a record compartment of the machine.

Figure 2 is a central longitudinal section through the machine.

Figure 3 is a section on line 3—3, Figure 1.

Figure 4 is a section on line 4—4, Figure 1.

Figure 5 is a fragmentary perspective view of the mid portion of the machine showing a shifting lever operated for advancing the strips and extracting the same sufficiently to be grasped by

the hands of the operator for further or continued withdrawal, the lever being shown in an intermediate position sufficient for advancing the strips for hand grasp.

Figure 6 is a vertical section similar to Figure 5 showing the parts in position at the end of a paper feeding stroke.

Figure 7 is a section similar to Figure 4 illustrating the parts in another stage of operation.

Figure 8 is a fragmentary plan view of the mid 10 portion of the machine with the margin frame removed, illustrating the relative positions between the writing table and sheet or strip feeding mechanism.

Figure 9 is a side elevation of the strip extractor mechanism and division wall with certain 15 portions of the strip extractor mechanism being broken away to illustrate the parts in rear thereof.

Figure 10 is a vertical section on line 10—10, 20 Figure 9.

Figure 11 is a section on line 11—11, Figure 9.

Figure 12 is a section on line 12—12, Figure 9.

Figure 13 is a section on line 13—13, Figure 3.

Figure 14 is a perspective view of the rock plate 25 with slide plate removed, viewed from division wall side.

Figure 15 is a perspective view of the slide plate looking substantially from the record compartment side thereof.

The present improvement is characteristic to a type of manifolding machine shown and described in Letters Patent No. 1,333,082, to A. Krauth, dated March 9, 1920, employing a hinge or swinging leaf member carrying depressible pins 35 or detents engageable respectively with register apertures in the web or strip operated upon for withholding the same against displacement upon a writing table of the machine and for relative registration and alignment of several webs 40 or strips in superposed arrangement.

The pins in their engagement through the aperture of the paper also serve as means for moving or advancing the strip or strips to withdraw the same sufficiently to be grasped by the 45 hand of the operator for continued withdrawal for a determined or measured length governed by the aperture spacing in the sheet with which the pins or detents automatically engage when in their normal sheet arresting position.

Referring to the drawings 1, 2 indicate the opposite side walls of the frame or casing of the machine with the bottom 3 and opposite end walls represented as formed or made up of a single sheet of metal. The casing furnishes a com- 55

partment for a supply pack of paper 4 in strip form and of a plural number of strips appropriately folded in zigzag arrangement in accordance with one of the methods employed for packaging the paper supply for machines of this class; or the paper supply may be packed in rolls, the rolls mounted and journaled upon holders within the casing or fixed to the side walls of the casing, or the paper furnished in any other manner with the packed form as illustrated, at present being preferable by the trade.

In the drawings, the machine is illustrated as loaded with a triplicate number of strips, the third strip of the series, as a record strip, being fed, after making the proper entries thereon, into a record compartment of the casing and re-folded into a pack. As the paper supply for autographic registers or manifolding machines in the packet or other methods of packaging, is a well known commodity in which the strips generally are punched with filing apertures at definite spacing apart longitudinally of the strips and the apertures utilized for bringing and maintaining the several sheets or strips in registry and alignment upon the writing table and also for cooperation with strip feeding and arresting mechanism, an extended explanation of such well known features need not be made herein.

The casing at the top for a portion of its length in the particular style of machine here-with illustrated, is equipped with a writing table 5 which can be either removed or elevated for access into the supply compartment. The strips are drawn from the supply compartment beneath the table over a roller 6 journaled in the side walls of the casing and thence over and upon the writing table in superposed relation. A margin frame 7 either hingedly or removably secured to the top of the casing extends over the writing table and spaced therefrom overlying the manifolding strips. As illustrated the side walls extend slightly above the plane of the table to serve as longitudinal guides of the paper strips, a common expediency in this class of machines.

The interior of the casing beneath the forward end of the writing table is provided with a partition wall 8 rigidly mounted on the base and side walls of the casing for supporting a feed roller and other parts of the strip feeding or extracting mechanism. A cross bar 9 riveted to the wall 8 has its end dowelled for rigid connection with the side walls; while the lower edge of the partition wall is angle flanged for securing the same to the bottom of the casing.

Similarly as disclosed in the aforesaid patent, the machine is provided with a swinging carrier or leaf 10 hingedly mounted upon a rod 11 extending across the base of the casing and supported within a pair of lugs 12 formed at an angle integral with the angle flange of the partition wall.

The swinging carrier or leaf 10 provides a hinged support for a pair of pins 13-13, each preferably mounted upon an ear or lug 14 bent laterally at an angle from the upper edge of a slide plate 15 slidably mounted upon the carrier 10. The pins are therefore unitarily movable with the slide reciprocable vertically upon the carrier for engaging and releasing the pins with and from the apertures in the strips and swinging with the carrier for conveying the strips to partially extract the same in a forward swing of the carrier, to extract or bring the forward

edge of the several strips from the machine for access by the operator for further or continued withdrawal manually.

The carrier 10 preferably has several lug hooks 16, stamped at an angle from the plane of the carrier, each engaged through an elongated slot 17 vertically in the slide plate slidably securing the slide plate to and parallel with the carrier. The upper pair of lug hooks 16 each has a spring 18 connected thereto with the opposite end of the spring engaged with a clip 19 stamped from the body of the slide plate (see Figures 3 and 7). The slide plate with its pins 13, as a unit, is therefore yieldingly depressible upon the carrier enabling the pins to automatically snap into or enter through the perforations in the paper strips upon the table when the apertures therein are brought in registry with the pins.

The carrier and slide plate normally are locked in a vertical position parallel with and to the wall 8 so that the pins when engaged through the aperture in the strips hold the same against displacement upon the writing table. In the normal position of the carrier, the slide plate with its pins in one stage of operation, as—during period of manually withdrawing the strips, is yieldingly sustained with the pins under tension bearing against the under side of the lower strip of the series ready to snap or enter the apertures in the strips when brought into registry therewith.

The pins in entering the apertures relatively aligning the several strips and automatically arresting the strip withdrawal for a length governed by the aperture spacing longitudinally of the strips.

The carrier and slide plate, as a unit, are locked to the partition wall 8 through a hand lever 20 pivoted upon the wall 8 by means of a hook latch 21 pivotally mounted upon a lug 22 extending or bent at an angle from the upper end of the carrier with the edge 23 of the carrier beneath the latch serving to limit the downward swing of the latch (see Figure 13).

The latch engages with the hand lever when the lever is in its normal idle position and is released upon depressing the hand lever. The upward stroke of the hand lever is limited by a hook shaped lug 24 punched or bent at an angle from the partition wall 8 (see Figures 3 and 9), with the hook portion of the lug 24 serving to hold the hand lever against lateral play, likewise the carrier and slide plate against vibration while latched.

A spring 25 at one end fixed to the wall 8 and its opposite end to the hand lever 20 is employed for normalizing the lever after depressed and released by the operator and similarly the swinging carrier 10 is normalized by a spring 26 (see Figure 10) having one end clipped or fixed to the carrier and the opposite end to the partition wall 8.

The hand lever 20 is provided with a laterally extended lug or tongue 27 engageable in depressing the lever with an inclined tongue or cam 28 stamped from the carrier for swinging the carrier forwardly away from the wall correspondingly swinging the pins engaged through the apertures in the paper strips for advancing or withdrawing the strip to project the same beyond the tearing edge of the cross bar 29 of the margin frame, so that it can be grasped by the operator as shown in Figure 7, for further or continued withdrawal or extraction of the strips. The tongue or cam 28 is shaped to 75

provide for a definite length of swinging stroke of the carrier with the free end of the tongue extending downwardly so as to continue engagement with the lug 27 of the hand lever, to 5 hold the carrier against retreat, while the hand lever depression is continued for engagement with a lug 30. The lug 30 is formed to extend at an angle from the rear side of the slide plate and through an opening in the carrier intersecting the lug 27 of the hand lever for connecting the slide plate with the hand lever for depressing the slide plate to disengage the pins from the apertures in the paper strips at the end of a paper feeding stroke of the carrier. 10 The slide plate when depressed is held or locked in its retreat position by a spring latch consisting of a spring metal blade 31 having its lower end fixed to the outer side of the slide plate and its opposite end provided with a laterally extended pin or bolt 32 engaged through an aperture in the slide plate and adapted to snap into a registering aperture 33 in the carrier as shown in Figures 10, 11, and 14.

The slide plate is unlatched in a return stroke 25 of the carrier, the latch pin 32 striking a lug 34 extending from the wall 8 under a pressure of the carrier normalizing spring thus forcing the pin from the aperture in the carrier allowing the slide plate to be retracted by the spring 30 18 which yieldingly urges the pins against the underside of the lowermost strip of the series for subsequently engaging with a pair of apertures in the strip when moved into registry therewith.

35 Insofar as described, the function and operation of the mechanism is similar to that disclosed in the aforesaid patent, in which the form lengths of all of the strips are extracted or issued from the machine. In the machine of the 40 present invention, one of the strips of the series as the lowermost thereof, designated as a record strip, is fed for a redeposit in the machine casting and into a record compartment 35 thereof.

The paper strips being scored or weakened 45 along the lines of fold in preparing the same for flat packaging and folded into zigzag arrangement, conditions the strip or makes it susceptible for self-refolding as it is fed into the record compartment against an abutment or 50 wall 36 for squaring the folded edges.

The feed or transmitting motion of the record strip is administered through the traction between the several sheets and with a roller 37 therebeneath, the roller frictionally contacting 55 with the lowermost sheet and yieldingly compressing the same against the cross bar at the forward end of the margin frame. The roller 37 is journaled in a slide bracket 38 slidably mounted upon the upper end of the partition wall 8. The roller is compressibly moved against the strips of paper under the tension of spring 25 when the bracket 38 is engaged by the hand lever 20. A stud 39 laterally extends from the hand lever 20 for engaging the lower edge of 60 an off-set end of the bracket 38. The roller compresses the paper strips against a longitudinal boss 40 depressed from the cross bar of the margin frame.

The bracket 38 is slidably secured to the wall 70 8 by a screw 41 engaged through an elongated slot 42 in the bracket and by a T-lug 43 projecting from the wall 8 and straddling a notch 44 in the bracket 38. When the hand lever 20 is depressed the bracket with its roller descends 75 by gravity retreating below the plane of the guid-

ing table and thus is released from its contact with the strips, and remains free therefrom during the period of mechanically extracting the sheets.

The pins 13 likewise when engaged through 5 the apertures in the strips extend through notches or openings in the forward end of the writing table and when depressed are brought below the frame of the writing table.

The forward end of the writing table is curved 10 downwardly for guiding and directly the record strips into the record compartment 35 and the record strip is also guided downwardly by a curved guard 45 as a cross wall portion of a cover or top for the record compartment which is either 15 removably or hingedly mounted upon the casing. A pendant 46 consisting of a piece of wire bent to V form with its opposite ends pivotally secured to the under side of the cover of the record compartment, aids in the refold of the 20 record strip which is fed in the record compartment.

The casing along one side of the writing table is provided with the usual compartment 47 for holding a supply of carbon or manifolding paper 25 which is distributed transversely over the writing table or platen between the several strips and clamped by the margin frame. The rear end of the writing table is slightly depressed or offset and provided with means for projecting the 30 approaching edge of the carbon strips against injury through the pulling traverse of the paper strips in the withdrawal thereof. The protectors for each carbon strip consist of a pair of leaves suitably anchored and overlapping the edge of 35 the carbon strip.

In operating the machine the paper strips are initially passed longitudinally over the platen or writing table, and adjusted so that the perforations of the several strips are in registry and 40 engaged over the pins 13. The margin frame in loading the machine is swung up or removed for free access to the strips, pins, and other parts and to thread or record the strip downwardly between the roller 37 and cross wall or guard 45, 45 thus following the general steps in the method of loading machines of this character.

For simultaneously advancing the several strips mechanically to protect the forward end of those of the series which are to be issued from the 50 machine for hand gravity by the operator to mechanically continue the withdrawal and simultaneously therewith feed the record strip in the record compartment, the hand lever 20 is depressed by the operator to its full limit of 55 stroke, and then immediately released. The downward or depressing movement of the hand lever disconnects the hand lever from the hook latch 21, releasing the swinging carrier 10. The hand lever engages with the inclined cam or 60 tongue 28 of the carrier swinging the carrier and its pin carrying slide plate as a unit forwardly, conveying the paper strips therewith to the limit of the forward swing of the carrier. The hand lever in its continued downward stroke sequentially after the carrier has been swung to the desired degree connects with the slide plate 15 through its interception with the laterally extended lug 30 of the slide plate depressing the 70 slide plate and thereby withdrawing the pins from the apertures in the paper strip, bringing the pins below the plane of the writing table and locked in such retreat position together with the slide plate by the spring latch 31, the lock pin 75

32 of the spring latch engaging into an aperture in the carrier.

Immediately upon release of the hand lever 29, after it has been fully depressed, the actuated parts will be automatically restored to their normal positions and the roller 37 urged against the strips through the engagement of the hand lever with the roller supporting bracket 38. The roller preferably has a yielding surface or periphery being formed of rubber so as to revolve under the traction with the lowermost strip of the series and traction between the several strips of the series so that the record strip will be correspondingly advanced as the upper strips of the series are manually withdrawn and until their withdrawal is stopped by the pins engaging with a successive set of apertures therein.

Having described my invention, I claim:

1. In a machine of the class described, a casing having a writing table for supporting one or a plurality of strips fed from a supply compartment in the casing, the strips when in a plural number being in a superposed arrangement upon the table and each provided with longitudinally disposed and determinately spaced aligning apertures, depressible pins located at the forward end of the writing table and at an angle thereto engaging the strip through the apertures thereof, a swinging frame supporting said pins and moving the pins forward to advance the strip, a depressible hand lever for swinging the frame and depressing the pins at the end of a forward stroke to disconnect the pins from the strips, a latch carried by said swinging frame for locking the pins in a depressed position, and means for automatically tripping said latch at the end of a retreat stroke of said swinging frame for releasing the locked pins.

2. In a machine of the class described, a casing having a writing table for supporting one or a plurality of strips fed from a supply compartment in the casing, the strips when in a plural number being in a superposed arrangement upon the table and each provided with longitudinally disposed and determinately spaced aligning apertures, depressible pins located at the forward end of the writing table and at an angle thereto engaging the strip through the apertures thereof, a swinging frame supporting said pins and moving the pins forward to advance the strip, hand operated means for swinging the

frame and depressing the pins at the end of a forward stroke to disconnect the pins from the strips, locking means for holding the pins in a depressed position during the retreat stroke of said swinging frame and means for automatically tripping said locking means at the end of a retreat stroke of said swinging frame to release the pins. 5

3. In a register, a casing provided with a platen over which a plurality of continuous form strips 10 may be disposed and a record compartment below the plane of the platen, a margin frame for said casing over the platen and stationery, feeding means having depressible pins for entering apertures in the stationery for limiting the 15 manual withdrawal of the stationery and initiating the feed of the stationery, a roller disposed at the front end of the platen for pressing the stationery against a front margin of the margin frame for transmitting a feeding action 20 of one strip to another so that the withdrawal of an issuing strip will cause a record strip to be propelled into the record compartment, a bracket supported within the casing movable laterally to the platen for journalling said roller, 25 and a spring urged lever normally engaging said bracket for yieldingly urging the roller against said margin frame and depressible for actuating said feeding mechanism and releasing said roller.

4. In a register, a casing provided with a 30 platen over which a plurality of continuous form strips may be disposed and a record compartment below the plane of the platen, a margin frame for said casing over the platen and stationery, means for feeding the stationery to advance its forward edge beyond the margin frame for manual grasp, a roller disposed at the front end of the platen for pressing the stationery against a front margin of the margin frame for transmitting a feeding action of one strip to 40 another so that the withdrawal of an issuing strip will cause a record strip to be propelled into the record compartment, a bracket supported within the casing movable laterally to the platen for journalling said roller, and a spring urged lever normally engaging the bracket for yieldingly urging the roller against said margin frame and depressible for actuating said feeding means and releasing said roller. 45

FRITZ G. DIESBACH.
